UNITED STATES PATENT OFFICE

2,512,793

CURTAIN ROD BRACKET

Ferdinand A. Gehret, Dayton, Ohio

Application March 29, 1946, Serial No. 658,248

3 Claims. (Cl. 243—265)

1

This invention relates to improvements in brackets for supporting curtain rods and has for its object to provide a bracket for supporting a curtain rod attached to the lower end of a curtain such as that usually found in connection with the glass part of a door.

It is particularly the object of this invention to provide an adjustable support for a rod attached to one end of a curtain and to support the rod in such a way that it will permit the movement or adjustment of the rod due to the shrinkage of the curtain.

It is a further object of this invention to provide in connection with a pair of brackets located at one end and the sides of the curtain a clamping member adapted to receive and hold a curtain rod. This clamping member may be shaped to receive either a round or flat rod.

These and other objects and advantages will appear from the following description taken in connection with the drawings, in which:

Figure 1 shows the lower part of a door with the glass therein to which the brackets are attached.

Figure 2 is a front elevation of the bracket with a clamp thereon.

Figure 3 is a side elevation of the bracket with two clamps thereon, one for holding the flat end of a rod, and the other for holding the round end of a rod.

The numeral 1 is used to designate the frame part of a door which has a glass therein. Over this glass part of the door is a curtain 2 supported in any suitable manner at its upper end to a part of the door. The numeral 3 is used to designate the edges of the glass. The lower end of the curtain has therein a rod 4 of any suitable form, shape and material. Usually these rods are flat at their ends so that they will not readily turn or rotate.

Supporting the ends of the rod 4 are brackets 5 shown in detail in Figures 2 and 3. These brackets are usually flat and are about six inches long with their ends off-set, as indicated by the numeral 6, to provide supports for the body parts 7 of the brackets so that the body parts are slightly spaced from the surface to which the brackets are attached.

On the body part 7 of the bracket is located a U-shaped clamp 8 adapted to fit over the bracket as shown in Figures 2 and 3. In one leg

2

of each clamp is a hole in which there is threaded a clamp screw 9 for gripping a rod and holding the clamp on the bracket. The clamp members 8 are U-shaped with their prongs usually flat.

5 There is also shown in Figure 3 a form of clamp 10 in which one arm of the U-shaped member has a trough or pocket 11 for receiving one end of a round rod or a rod with a ball on the end of it. In this clamp there is a screw 12 for forcing the 10 end of the rod against the body 7 for holding the clamp in a fixed and adjusted position on the bracket. The ends of the bracket have holes 13 therein through which screws 14 pass into the wood of the door or any other surface to which the clamp is attached.

What I claim is:

1. In a curtain rod bracket, an elongated member having each end off-set for supporting the member on a window frame, a U-shaped rod 20 clamping member on said first named member, said clamping member having a leg engaging said first named member and means in the other leg for adjustably holding said clamping member on the first named member.

25 2. In a curtain rod bracket, a bracket at each end of the rod, and means on each bracket to engage the end of the rod for clamping it, said means consisting of a U-shaped member fitting over the end of the rod and having one leg engaging the bracket, and a clamping instrumentality in the other leg of said U-shaped member for clamping the rod to the bracket.

3. In a curtain rod bracket, an elongated member, a U-shaped clamp member on said first 35 named member, one leg of said U-shaped member having a pocket therein for the end of a curtain rod, and means operating in the pocket to clamp the rod against the other leg of the U-shaped member.

40 FERDINAND A. GEHRET.
